CLAIM

The ornamental design for a cell phone charging cable storage container, as shown and described.

DESCRIPTION

FIG. 1 is top exploded perspective view of our new design for a cell phone charging cable storage container.

FIG. 2 is a side view thereof.

FIG. 3 is a bottom exploded perspective view thereof.

FIG. 4 is a right side view of the top portion of the design thereof.

FIG. 5 is a top perspective view thereof.

FIG. 6 is a bottom perspective view thereof.

FIG. 7 is a top view thereof.

FIG. 8 is a bottom view thereof.

FIG. 9 is a left side view thereof.

FIG. 10 is a right side view of the bottom portion of the design in FIG. 1.

FIG. 11 is a left side view thereof.

FIG. 12 is a front view thereof.

FIG. 13 is a perspective view thereof.

FIG. 14 is a top view thereof; and,

FIG. 15 is a bottom view thereof.

1 Claim, 15 Drawing Sheets
